BOTTLE CARRIER OR THE LIKE

Morris A. Frankel, Teaneck Township,
Bergen County, N. J.

Application February 10, 1955, Serial No. 34,441

Term of patent 14 years

(Cl. D58—5)

Fig. 1

I claim:

The ornamental design for a bottle carrier or the like, as shown.
